UNITED STATES PATENT OFFICE.

GEOFFREY B. LEHY, OF MEDFORD, MASSACHUSETTS.

ELECTRIC SIGNALING APPARATUS.

SPECIFICATION forming part of Letters Patent No. 431,597, dated July 8, 1890.

Application filed May 21, 1889. Serial No. 311,594. (No model.)

To all whom it may concern:

Be it known that I, GEOFFREY B. LEHY, of Medford, county of Middlesex, State of Massachusetts, have invented an Improvement in Electric Signaling Apparatus, of which the following description, in connection with the accompanying drawings, is a specification, like letters and figures on the drawings representing like parts.

10 This invention has for its object to construct a signaling apparatus for various uses, as burglar-alarms and the like.

In accordance with this invention two primary circuits are employed leading from a single set of batteries. One of the said primary circuits includes or contains one or more circuit-changing devices and a receiving-instrument, as an electro-magnet, and the other primary circuit includes or contains a receiving-instrument, as an electro-magnet, the armature or armatures thereof being arranged to control an alarm-circuit containing a bell or other suitable alarm or indicating-signal, and may be itself an indicating-signal. One 25 of the primary circuits contains a suitable resistance-coil, and when removed, short-circuited, or shunted out by any cause other than a break in the line the circuit containing it is strengthened and its receiving electro-magnet attracts the armature; but when said primary circuit is broken the entire battery force passes over the other primary circuit, and by the increase in strength its receiving electro-magnet attracts its armature, so that whenever the condition of the primary circuit containing the circuit-changing device is in any way changed the fact is made known by the receiving electro-magnets and by the alarm and other mechanism controlled by it. Suitable 35 devices are preferably employed to cut out or render inoperative the receiving electro-magnets at will and also for determining by the indicating-signal whether or not the battery is in proper condition.

40 Figure 1 shows in diagram a signaling apparatus embodying this invention; Fig. 2, a modification to be referred to.

The signaling apparatus, as herein shown, is especially designed for protecting a safe, 45 or it may be a room or compartment at a distant point. The main battery a has leading

from it two primary circuits a' a^2 , one of which, as a^2 , for instance, includes the compartment to be protected, and contains one, or it may be several, circuit-changing devices, as a^3 , controlled by the door of the safe or otherwise. The compartment herein represented in dotted lines is a safe, and the primary circuit a^2 contains in the safe a resistance-coil b . The primary circuit a^2 also contains a receiving 55 electro-magnet a^4 . The primary circuit a' contains a receiving electro-magnet a^5 , shown in Fig. 1 as placed face to face with relation to the receiving electro-magnet a^4 , and an armature a^6 , attached to an armature-carrying 60 lever a^7 , pivoted at a^8 , is located between the poles of the receiving electro-magnets and held free from contact with either pole, or substantially at a point intermediate between the poles, by springs 2 3, which are preferably 65 adjustable so that more or less tension may be brought on the armature at either side, as desired.

The armature-carrying lever a^7 is herein shown as having attached to it two contacts 75 4 5, which engage the contacts 6 7 when moved in one or the other direction. The contacts 6 7 are included in an alarm-circuit c , herein shown as including the local battery c' and the bell c^2 , or it may be another indicating- 80 instrument.

It is the intention that the two primary circuits a' a^2 shall be of substantially equal resistance; but the springs 2 3, being adjustable as described, this feature is not absolutely essential.

The armature-carrying lever may and preferably will bear a disk d , which moves back of suitable openings formed in a fixed plate d' or an equivalent thereof. 90

In operation, should any accident happen to the primary circuit a^2 , so that in any way its strength should be increased—such, for instance, as shunting out the resistance-coil or by contact with another wire—the armature a^6 will be attracted toward the receiving electro-magnet a^4 , and hence closes at 5 6 the alarm-circuit; and if the primary circuit a^2 should be broken the armature will be attracted toward the receiving electro-magnet a^5 , and by the contacts 4 7 will also close the alarm-circuit. It will thus be seen that any 95 100

change in the condition of the primary circuit a^2 will be made known.

I have herein placed one of the contacts, as 7, a little farther from the armature-carrying 5 lever or from the contact 4 than the opposite contact, so that when a wire is broken and the armature held by the receiving electro-magnet a^5 it is completely out of the field of the receiving electro-magnet a^4 , or substantially 10 so, and hence will not automatically return, as it will do under all other conditions. A hand-lever e is pivoted at e' , being held by friction, which lever co-operates with two contacts e^2 to maintain the continuity of the 15 alarm-circuit c ; but arranged directly above the said lever e are two contacts e^3 , which, when the said lever is brought into contact therewith, short-circuits the battery by the 20 wires 8 9. I have also herein shown an electro-magnet f as included in the primary circuit a' , the armature of which also controls the alarm-circuit c and makes known when the strength of the battery is impaired by its 25 armature falling.

25 The signaling apparatus herein shown is applicable for many purposes in addition to burglar-alarms, such, for instance, as railway signaling and the like.

In Fig. 2 I have shown two receiving electro-magnets a^4 a^5 , located side by side, and two armatures, as 20 20, attached to a lever or bar 22, pivoted at 23, and, if desired, the armature may be attached to independent levers or bars.

35 I claim—

1. In an electric signaling apparatus, the combination, substantially as described, of a main battery and two normally-closed primary circuits leading from it, a receiving 40 electro-magnet in each of said circuits located adjacent to each other, the armatures of which are held away from their poles by a force greater than the normal attractive force of the magnets, and stops located at opposite 45 sides of the armature-carrying lever, but at different distances therefrom, when the latter is in its normal position to enable the ar-

mature to be retracted farther away from the poles of one magnet than the other.

2. In an electric signaling apparatus, the combination, substantially as described, of a main battery and two primary circuits leading from it, a receiving electro-magnet in each of said circuits arranged face to face, an armature arranged between the said receiving electro-magnets and a local or alarm circuit controlled by the movement thereof in either direction, a suitable resistance in one of the said primary circuits, and a circuit-changing device also in said primary circuit, and a manually-operable device for short-circuiting the main battery.

3. In an electric signaling apparatus, the combination, substantially as described, of a main battery and two primary circuits leading from it, a receiving electro-magnet in each of said circuits arranged face to face, an armature arranged between the said receiving electro-magnets and a local or alarm circuit controlled by the movement thereof in either 65 direction, a suitable resistance in one of the said primary circuits, and a circuit-changing device also in said primary circuit, and a manually-operable device for short-circuiting the main battery and the local or alarm circuit.

4. In an electric signaling apparatus, the combination, substantially as described, of a main battery and two normally-closed primary circuits leading from it, a receiving 80 electro-magnet in each circuit, the armatures of which are held away from their poles by a force greater than the normal attractive force of the magnets and which, when brought near to or against the pole of one magnet, is substantially out of the attractive field of the other, substantially as described.

In testimony whereof I have signed my name to this specification in the presence of two subscribing witnesses.

GEOFFREY B. LEHY.
